(57) **CLAIM**

We claim the ornamental design for a square contoured fountain, as shown and described.

DESCRIPTION

FIG. 1 is a perspective view of a square contoured fountain embodying our invention;

FIG. 2 is a top plan view thereof;

FIG. 3 is a left elevation view thereof;

FIG. 4 is a front elevation view thereof;

FIG. 5 is a bottom plan view thereof; and,

FIG. 6 is a rear elevational view of thereof.

The portions of the design shown in broken lines are for illustrative purposes only and form no part of the claimed design.
